UNITED STATES PATENT OFFICE.

ROBERT BLACKBURN, OF CHORLEY, ENGLAND, ASSIGNOR TO PARENT CATERPILLAR COMPANY, LIMITED, OF LONDON, ENGLAND.

ROUNDABOUT AND LIKE AMUSEMENT APPARATUS.

Application filed September 24, 1925, Serial No. 58,404, and in Great Britain September 25, 1924.

This invention relates to roundabouts and like amusement apparatus, and has for its object to provide an apparatus of this kind of a novel and improved construction.

5 According to the invention, a rotatable platform is provided on which are mounted a number of cars each adapted to hold several passengers for whom seats are provided.

10 A cover, which may suitably be in the form of a grotesque figure head, is supported over each car and is adapted to be raised and lowered. The cars are preferably adapted to run on a track and the cover or head 15 is adapted to be rotated relatively to the car so as to give the passengers a sensation of rotation. This rotation may be controllable and, in combination with this cover, by which the passengers may be plunged into 20 darkness or exposed to the light at the will of the operator, the bottom of the car may be formed with a grating and light projectors and fans may be arranged along the track.

25 The cover or figure head will preferably be composed of strong canvas mounted on a collapsible frame, made on the umbrella principle over which would be stretched or laid the rubber or other form of figure head.

30 To add to the appearance, the sides of the car would be cylindrical and painted white to represent a collar. The figure heads may also be provided with dummy head-phones and within the head, or elsewhere in the car, 35 may be arranged a "loud speaker" either for the purpose of providing music, or weird noises to add to the confusion caused by the flashes of light and gusts of air provided in the course of the ride, or telephone head 40 pieces may be provided within the car for use by the passengers.

The accompanying drawings show one form of amusement apparatus made according to the invention in which:

45 Fig. 1 is a general and part sectional elevation one head being shown in the lowered position.

Fig. 2 is a plan.

Fig. 3 is an elevation of one of the cars.

50 Fig. 4 shows a plan of the gearing on the axle of the car.

Fig. 5 shows in sectional elevation the mechanism for raising the covers or heads.

55 The apparatus comprises a platform *a* rotatably mounted about a central column.

On the platform, arranged at intervals, are cars *b* each circular in shape and secured to the platform.

The sides of the cars are about 2 ft. 6 ins. high and an entrance door *c* is provided in each car. Below each car is provided a trolley *d* running on a track *e* arranged below the platform *a* and in the centre of the car is a vertical column *f* rotatably mounted therein and provided with worm gearing *g* by which it is coupled for rotation to the axle *h* of the trolley. The vertical columns *f* are connected by links *k* to one another and by tie rods *m* to the central column. The head, formed of strong canvas stretched on a frame of umbrella construction is mounted on a sleeve *n* slidably mounted on the upper portion of the vertical column *f* and is adapted to be rotated thereby. A lifting cable *o* passes down through the vertical column *f* to a swivel or like and by means of a cross pin in a slot in the column *f* is adapted to raise and lower the head. The cables pass along the respective tie rods *m* to a common swivel sleeve *p* on the central column and the heads are adapted to be raised and lowered by a screw *q* and nut *r* on the central column. Two double seats are provided in each car, back to back, on opposite sides of the vertical column *f*. 85 Gratings are provided in the floor of the car and suitably arranged around the track will be blowers and light projectors over which the gratings will pass. The heads are each provided with dummy head phones, though if desired a loud speaker may be incorporated in them. A loud speaker or like means will preferably be provided within the car, either in the head or under the seat and will be automatically operated or controlled by 90 the operator.

A description of a ride is as follows:

Four people walk on the platform and get in a car, two seated at each side of the upright shaft back to back directly in the centre of the car. The head has already been hoisted up a distance of three or four feet to enable the passengers to get seated in the car. As the platform begins to move the head revolves but does not descend until all 100 the fares are collected. Then the heads are lowered and go on revolving, this giving the effect as though the whole car was revolving. Underneath the platform on the ground, various pipes and strong lights are placed at 105 110

intervals, and as the cars move along, different sensations are produced, through the perforated bottom of the car. In the extreme top of the head a loud speaker will be installed producing wireless music or other noises. On the outside of the head, a large pair of dummy head-phones will be fixed. As the platform stops the heads ascend and the passengers get out.

10 The combination of wind, light, noises and darkness, may be arranged to give the effect of a storm, and in fact an infinite variation of sensations may be produced. Microphones may be arranged in each car connected to the loud speaker in another car, being either connected for inter-communication, or so that the reply goes to a different car so as to add to the fun by the confusion of the answers.

15 20 It has been proposed in amusement apparatus in which a ride is provided in a car, to arrange a collapsible canopy which travels with the cars and can be unfolded to close upon the cars and their passengers or folded 25 to expose them to view and where the cars traverse an undulating track the canopy has been arranged to rise and fall with the cars. Such canopy has been provided with partitions to form separate compartments for 30 each car, but where this is done the canopy can have no movement relative to the cars other than in folding and unfolding. It has also been proposed to provide a separate canopy for each car, to obtain the motion 35 for the folding and unfolding of the canopy from the motion of the cars and to provide

wind blasts and flickering light effects within the cars.

No claim is made to any such construction of canopy and no claim is made to the mechanism per se for obtaining the raising and lowering of the covers in this invention.

What I claim is:—

1. An amusement apparatus comprising a circular track, a rotary platform on wheels engaging said track and a series of cars carried by said rotary platform, seats in said cars, a vertical shaft projecting through each car with means operated by the travel of said car for rotating said shaft, a collapsible canvas cover carried by said shaft and turning therewith, and means for moving said cover vertically on said shaft while said shaft is being rotated, substantially as shown and described. 55

2. An amusement apparatus comprising a circular track, a rotary platform on wheels engaging said track and a series of cars carried by said rotary platform, seats in said cars, a latticed floor, adapted to permit the passage of light and air, provided in front of each seat, a vertical shaft projecting through each car with means operated by the travel of said car for rotating said shaft, a collapsible canvas cover carried by said shaft and turning therewith, and means for moving said cover vertically on said shaft while said shaft is being rotated, substantially as shown and described. 60 65

In testimony whereof, I affix my signature. 70

ROBERT BLACKBURN.
